UNITED STATES PATENT OFFICE

MALCOLM K. PARKHURST, OF NEW YORK, N. Y., ASSIGNOR TO BROWN & SHARPE MFG. CO., OF PROVIDENCE, RHODE ISLAND

MICROMETER CALIPER

Application filed March 10, 1928. Serial No. 260,588.

This invention relates to certain new and useful improvements in micrometer calipers, and the primary object thereof is to provide a caliper which can be accurately read thereby positively eliminating any guess work on the part of the operator.

It frequently occurs that the marks from zero upward on the outer sleeve come to a position in which the lines of reading are between two of the marks, and the user ordinarily then guesses as to what the reading might be. The present invention therefore aims to eliminate this guess work by the provision of an auxiliary sleeve, the reading line of which is movable by virtue of rotation of the auxiliary sleeve so that the readings on the latter will indicate the exact reading in connection with the reading of the outer sleeve.

The invention, therefore, eliminates the disadvantages heretofore had with the ordinary vernier micrometer caliper, the three outstanding disadvantages of which have been the inconvenience of having to compare a number of lines in determining the reading; the annoyance of having to reverse the micrometer, or turn same over in order to read same; and finally the necessity of removing the micrometer in gauging large or stationary work. In the latter regard, it will be understood that in such instances, which are very common, the practice of setting the clamp ring and then removing the micrometer seriously affects the accuracy of a precision instrument, which procedure also has a detrimental effect in causing undue wear on both the anvil and the spindle.

In the drawings:—

Figure 1 is a side elevation of the invention;

Figure 2 is a rear end elevation;

Figure 3 is a view similar to Figure 1 partly broken away and in section, and

Figure 4 is a section on line 4—4 of Figure 3.

In proceeding in accordance with the present invention, the usual yoke 1 is employed having an anvil 2 at one end, which is opposed by the customary spindle 3. The spindle 3 has a barrel or sleeve 4 associated therewith,

which latter has the customary graduations or readings 5, the large sub-divisions of which may be divided into .10 inches and the smaller sub-divisions into .025 inches and further has a rotatable barrel or sleeve 6 provided with graduations or reading lines 7 substantially divided into 25 divisions which cooperate with the fixed lines 5 of the barrel 4.

A yoke 8 is connected to the main yoke 1 and is preferably partially inset with relation to the latter, as shown in Figure 3 and is secured in position by means of a screw 9. The yoke has a sleeve 10 which is received in a hole 11 provided therefor in one of the sides of the arm of the yoke, which sleeve provides a bearing for the inner end of a spindle 12, the latter carrying a spool 13, the spool being tensioned by means of a coil spring 14.

In accordance with the present invention, the barrel 4 instead of being fixed as in the prior art, is capable of slight oscillatory movement and accordingly same has a rigid arm 15 connected thereto by means of which oscillatory movement is imparted to the barrel 4. The arm 15 has a forked end 16 which latter straddles a pin 17 eccentrically mounted on the spool 13. A stop pin 18 is carried by the yoke 8 and is adapted to engage one side of the arm 15 to limit movement of the latter in one direction. The pin 17 is formed integral with the spindle, and the latter has a collar 18' at the outer end of the pin 17, the collar in turn being integral with the enlarged outer end 19 of the spindle. An auxiliary barrel 20 comprising an auxiliary measuring means is fixed on the outer end of the spindle and is held against the collar 18 by means of a screw 21. The barrel has graduations 22 thereon which are adapted to register with a fixed reading line 23 on the yoke 8 as depicted in Figure 1. The small oscillatory barrel or sleeve 20 is graduated 0, 1, 2, 3, 4, 5, 6, 7, 8, 9, 0, each graduation corresponding to $1/10,000''$. The complete range from 0 to 0 is covered by but one-half a revolution of this oscillatory sleeve, the spring 14 maintaining the barrel directly on the 0 nearest 9.

It will be noted that the sleeve 4 is independently mounted and directly connected

to the auxiliary structure by means of the lever arm 15, whereas the sleeve 6 is directly connected to the spindle 3 and therefore has no connection with the rotating sleeve 4, which latter is normally held in the zero position by reason of the spring action of the auxiliary member through the lever 15.

In operation, the micrometer is set, for example, to give a reading of .2767", the oscillatory sleeve 20 remaining in its normal position, whereupon it will be seen that the coincidence line on the barrel 4 does not quite coincide with the .002 mark on the barrel 6. The oscillatory barrel 20 is now turned, whereupon the coincidence line on the barrel 4 approaches the .002 mark on the barrel 6. At a point 7 or .0007 on the barrel 20, the coincidence line on the barrel 4 is in direct alignment with the line on the barrel 6. Thus it is merely necessary to add the .0007 to the original reading of .276 which gives .2767".

As is evident, there is no advancement of the spindle 3 upon turning the oscillatory barrel 20, the sole function of the latter being merely to gauge by ten-thousandths any discrepancy of exact alignment between the coincidence line on the barrel 4 and a one-thousandth mark on the barrel 6.

It will be noted that in turning the barrel 20, same rotates barrel 4 in the same direction as that of barrel 20, this eliminates any tendency of the barrel 20 to loosen and thereby give an incorrect reading. By virtue of the automatic restoration to normal or neutral of the barrel 20, there can be no error due to forgetfulness on the part of the user accordingly. Should measurements of .001" only be taken, then the usual procedure is followed, the barrel 20 being disregarded.

Having thus described my invention what I claim as new and desire to secure by Letters Patent is:—

1. In a micrometer caliper, a yoke having an anvil, a spindle carried by said yoke, an oscillating sleeve on the spindle, a graduated rotary sleeve on the first named sleeve and fixed to said spindle, a yoke fixedly carried by the main yoke and having a reading line, an auxiliary graduated sleeve, a spindle connected to the second yoke and having the auxiliary sleeve fixed thereon in cooperating relation to said reading line, a slotted arm fixed on the oscillatory sleeve, a spool on the second spindle, tensioning means for said spool, a collar on the second spindle and having an eccentric pin engaged in the slot of said arm, and a stop for the arm carried by the second yoke.

2. In a micrometer caliper, a yoke having an anvil, a spindle carried by said yoke, a graduated oscillatory sleeve on the spindle, a graduated rotary sleeve on the first sleeve and fixed to said spindle, a member fixedly carried by the yoke and having a reading line, an arm fixed on the oscillatory sleeve, a spin-

dle carried by said member, an auxiliary sleeve fixed on the second spindle and having graduations cooperating with said reading line, means carried by said second spindle to engage and operate the arm upon turning of the auxiliary sleeve, and spring tensioned means for the second spindle to restore the latter and thereby the auxiliary sleeve to normal position subsequent to operation of the latter.

3. In combination with a caliper having a rotary graduated sleeve and an oscillatory graduated sleeve cooperating therewith, a graduated auxiliary sleeve disposed adjacent the first named sleeve, said caliper having a fixed reading line for cooperation with the auxiliary sleeve, means connected to the auxiliary and oscillatory sleeves to operate the latter by the former, and means to automatically restore the said two last named sleeves to normal position subsequent to operation thereof.

4. In combination with a caliper having a pair of cooperating graduated sleeves each rotatable independently of the other, auxiliary means to read measurements between the graduations of said sleeves and means actuated by said auxiliary means to effect relative turning movement of one of the sleeves independent of the other to bring the said graduations of the sleeves into register thereby to enable reading of the difference between said graduations on the auxiliary means.

5. In combination with a caliper having graduated main measuring means, auxiliary measuring means, and means operable by the auxiliary means to effect register of the graduations of the main measuring means thereby to indicate on the auxiliary measuring means the measurement existing between adjacent graduations of the main measuring means so as to enable reading of said measurement on the auxiliary means, and means to automatically restore the auxiliary means to normal position subsequent to operation thereof.

6. In combination with a caliper having a pair of cooperating graduated relatively rotatable sleeves, auxiliary means to read measurements between the graduations of said sleeves, and means actuated by said auxiliary means to effect relative movement of the sleeves to bring the said graduations of the latter into register thereby to enable reading of the difference between said graduations on the auxiliary means, and means to automatically restore the auxiliary means to normal position upon release thereof following operation.

7. In combination with a caliper having a pair of cooperating movable means for obtaining primary measurements, auxiliary means for obtaining secondary measurements, means to mount the auxiliary means for movement, means connected to one of the

pair of means and to the auxiliary means for effecting movement of one of said pair of means by movement of auxiliary means independently of the other of said movable means, and means for restoring the auxiliary means and thereby said one of the pair of means to initial position following operation of the auxiliary means.

8. In combination with a caliper having a pair of cooperating means each movable independently of the other for obtaining primary measurements, auxiliary means for obtaining secondary measurements, means to mount the auxiliary means for movement, and means connected to one of the pair of means and to the auxiliary means for effecting movement of said one means independently of the other of said movable means by the auxiliary means.

9. In combination with a caliper having rotary graduated sleeve and an oscillatory graduated sleeve cooperating therewith, a graduated auxiliary sleeve disposed adjacent the first named sleeve, said caliper having a fixed reading line for cooperation with the auxiliary sleeve, means connected to the auxiliary and oscillatory sleeves to operate the latter by the former independently of said rotary graduated sleeve and means to automatically restore the oscillatory and auxiliary sleeves to normal position subsequent to operation thereof.

10. In a caliper of the character described, a rotatable spindle, a graduated sleeve fixed to said spindle, a graduated oscillatory sleeve within said rotatable sleeve, auxiliary measuring means, means connecting the oscillatory sleeve and auxiliary measuring means whereby to move said oscillatory sleeve independently of the rotatable sleeve to indicate measurements existing between the graduations on the spindle sleeve and the oscillatory sleeve and means to automatically restore the oscillatory sleeve and auxiliary measuring means to normal position.

In testimony whereof I have signed my name to this specification.

MALCOLM K. PARKHURST.
